SCALE

Charles S. Schroeder, Philadelphia, Pa., assignor
to The Yale & Towne Manufacturing Com-
pany, Stamford, Conn., a corporation of Con-
necticut

Application July 30, 1947, Serial No. 764,641

7 Claims. (Cl. 308—2)

1

This invention relates to a weighing scale, and more particularly, to means for limiting the movement between a knife edge pivot member and a beam bearing of the usual well known weighing scale.

Those skilled in the art know that in weighing scales it is necessary to employ knife edge pivot members on which beams, levers or the like are supported for pivotal movement through bearings that rest against the knife edges of the said pivot members. In this way, the beams, levers, or the like may transmit a load to a lever or other part carrying the knife edge pivot member, while allowing some movement of the parts relatively to one another.

In assemblies of the particular class, it is desirable to limit the longitudinal movement of the beam and its bearing relatively to the knife edge member. This longitudinal movement, when it takes place, comprises a sliding movement of the beam and its bearing on the knife edge of the knife edge pivot member. Naturally, it is necessary that this limiting action take place without the development of friction, since friction will interfere greatly with the proper action of the scale. It is the object of my invention to contribute limit means of the class described that will operate with a minimum of friction.

As a feature of my invention, I utilize a knife edge pivot member whose ends flare outwardly from the base thereof toward the knife edge thereof, so as to form a peak at each end of the knife edge pivot member. Those skilled in the art will appreciate that in some assemblies only one end of the knife edge pivot member need be so formed.

As a further feature of my invention, I utilize a limit member having a surface or surfaces adapted to coact with the said peak or peaks, the coaction being such that a minimum of friction must naturally develop, since the contact between the limit member and the peak is a point contact.

While it is the main feature of my invention to utilize the particular combination of a knife edge pivot member and limit member set forth, those skilled in the art will appreciate that it is possible to use other cooperating arrangements of a limit member and a knife edge pivot member embodying the basic concept of my invention; that is, the utilization of surfaces coacting with a minimum of friction. Therefore, this invention should not be limited merely to the utilization of the particular surfaces that I believe yield the best results.

2

As a still further feature of my invention, the limit member is preferably in the form of a cap adapted to coact with the beam bearing and having flanges overlying the ends of the knife edge pivot member. As a still further feature of this part of the invention, the limit member or cap, as I call it, is adapted for movement relatively to the beam bearing so as to adjust itself to a proper operating position.

I have thus outlined rather broadly the more important features of my invention in order that the detailed description thereof that follows may be better understood, and in order that my contribution to the art may be better appreciated.

There are, of course, additional features of my invention that will be described hereinafter and which will form the subject of the claims appended hereto. Those skilled in the art will appreciate that the conception on which my disclosure is based may readily be utilized as a basis for the designing of other structures for carrying out the several purposes of my invention.

Referring now to the drawings, Fig. 1 is a section through a portion of a typical scale platform mounting assembly, showing my invention in such an assembly. Fig. 2 is a cross section of Fig. 1 taken along lines 2—2. Fig. 3 is an exploded view of the parts utilized in my invention. Fig. 4 is an enlarged view showing the point contact between the limit member and the knife edge pivot member, forming the basis of my invention.

Referring now more particularly to the drawings, reference numeral 10 indicates a part of the main frame surrounding the movable platform of the scale. Welded thereto and forming a portion thereof is a vertical structural member 11, and welded to this vertical structural member at 12 is what is termed a corner block 13. Corner block 13 is formed with a bore 14 in which is supported a corner bearing pan 15. The main lever of the scale is designated by reference numeral 16, and carries a knife edge pivot 17 resting on the corner bearing pan. A suitable limit bolt 18 carried by a bracket 19 on structural member 11 prevents upward movement of the main lever 16 and its knife edge pivot member 17 from the pan 15. Insofar as I have described my scale, it merely utilizes those features well known and understood by those skilled in the art.

Welded to the main lever 16 is a main lever knife bracket 20 comprising a pair of spaced plates 21 best illustrated in Fig. 3 as suitably reinforced by an end plate 22. The plates 21 are

formed with holes 23 and with retainer slots 24. Secured within the retainer slots 24, and bridging the space between the plates 21, is a knife edge pivot member 25. It is usual in the art to stake the knife edge pivot member 25 securely into position relatively to the plates 21 of the bracket 20 so that the knife edge pivot member will not move longitudinally on the said bracket 20.

A beam bearing 26 formed with a bearing groove 27 is then placed on the knife edge 28 of the knife edge pivot member 25. Coacting with the beam bearing 26 is what I term a load suspension link 29 having ears 30 formed with bores 31. These bores 31 are adapted for alignment with a bore 32 of the beam bearing 26, and through the aligned bores 31, 32 there is inserted a pin 33 held against endwise movement relatively to the suspension link 29 and beam bearing 26 by cotter pins 34. A cross bar 35 lies lengthwise in the openings 23 of the plates 21 of bracket 20 and rests at its center on the bearing surface 36 of the load suspension link 29, as is probably best seen in Fig. 1. The cross bar 35 is formed with square ends 37 adapted for coaction with the square notches 38 of a suspension bracket 39, this suspension bracket 39 being adapted to support in turn what I term the top frame 40 of the scale.

It is now obvious that through the suspension bracket 39, the load placed on the top frame 40 is applied to the cross bar 35, and that through the cross bar 35 the load is in turn applied to the load suspension link 29. It then follows that through the load suspension link 29 the load is applied to the beam bearing 26 and then through the knife edge pivot member 25 to the main lever knife bracket 29. Of course, through this main lever knife bracket 29 the load is then applied to the main lever 16.

For limiting endwise movement of the beam bearing 26 and its surface 27 relatively to the knife edge pivot member 25, I utilize what I term a link end thrust cap 41 having ears 42 and end flanges 43. The ears 42 are pierced at 44 for the pin 33 so that when the pin 33 secures the load suspension link 29 to the beam bearing 26, it simultaneously secures the link end thrust cap 41 in position. Of course, the cap 41 will be free to move pivotally relatively to the pin 33 so as to adjust itself into a proper operating position.

The ends of the knife edge pivot member 25 are tapered outwardly towards the knife edge 28 as is best illustrated in Figs. 1 and 4. As a result, each end of the knife edge pivot member 25 will terminate in the form of a peak 45. Each of the said peaks 45 is adapted for coaction with a flange 43 of the cap 41 as is best shown in Fig. 4, this coaction being in the form of a point contact between the parts. Those skilled in the art will understand that through a point contact a minimum of friction is developed between a flange 43 of cap 41 and one of the peaks 45 of the knife edge pivot member 25. Therefore, should one of the flanges contact one of the peaks 45, the parts will coact to limit any further movement in a particular direction between the beam bearing 26 and the knife edge pivot member 25. While effective limiting action will result, the friction between the parts will be at a minimum because of the point contact between the flange 43 and the peak 45.

I believe that the simplicity of my invention and the ease with which it is fabricated and utilized and assembled in a scale, will now be quite apparent to those skilled in the art.

I now claim:

1. In a scale of the class described, a knife edge pivot member, a flat undersurface on the base of said knife edge pivot member of greater longitudinal extent than the knife edge of said knife edge pivot member, a supporting member having a flat upper surface upon which the flat undersurface of said knife edge pivot member rests, a beam having a bearing surface bearing against the knife edge of said knife edge pivot member, a limit member carried on said beam for limiting endwise relative sliding movement between said knife edge pivot member and beam and thereby limiting lateral relative movement between said beam and said supporting member, said knife edge pivot member flaring endwardly outwardly from its base towards its knife edge to present a peak or point surface to a surface of said limit member whereby to reduce to a minimum friction between said limit member and said knife edge pivot member upon contact therebetween.
2. In a scale of the class described, a knife edge pivot member, a beam having a bearing surface bearing against the knife edge of said knife edge pivot member, a cap for said beam, a pivot shaft bearing on said beam in an axis transverse of the knife edge of said knife edge pivot member and engaged with said cap for pivotally securing said cap to said beam, flanges formed on said cap adapted to overlie the opposed ends of said knife edge pivot member for limiting endwise relative sliding movement between said knife edge pivot member and beam, said knife edge pivot member flaring endwardly outwardly at each end from its base towards its knife edge to present a peak or point surface to each of the flanges of said cap whereby to reduce to a minimum friction between said cap and said knife edge pivot member upon contact therebetween.
3. In a scale of the class described, a knife edge pivot member, a beam having a bearing surface bearing against the knife edge of said knife edge pivot member, a bearing pin traversing a bore in said beam transverse of the axis of its bearing surface and said knife edge, a load suspension link having opposed legs supported by said pin whereby a load is applied to said beam, a cap for said beam, opposed ears formed on said cap and having bores for said bearing pin whereby said cap is secured to said beam while adapted for some movement of adjustment relatively thereto, flanges formed on said cap adapted to overlie the opposed ends of said knife edge pivot member for limiting endwise relative sliding movement between said knife edge pivot member and beam, said knife edge pivot member flaring endwardly outwardly at each end from its base towards its knife edge to present a peak or point surface to each of the flanges of said cap whereby to reduce to a minimum friction between said cap and said knife edge pivot member upon contact therebetween.
4. In a scale of the class described, a knife edge pivot member, a beam having a bearing surface bearing against the knife edge of said knife edge pivot member, a cap for said beam, a pivot shaft bearing on said beam in an axis transverse of the knife edge of said knife edge pivot member and engaged with said cap for pivotally securing said cap to said beam, flanges formed on said cap adapted to overlie the opposed ends of said knife edge pivot member for limiting endwise relative sliding movement between said knife edge and beam, said knife edge having its end surfaces coacting with said flanges so shaped relatively to

the shaping of said flanges whereby to minimize friction inherent upon contact therebetween.

5. In a scale of the class described, a knife edge pivot member, a beam having a bearing surface bearing against the knife edge of said knife edge pivot member, a bearing pin traversing a bore in said beam transverse of the axis of its bearing surface and said knife edge, a load suspension link having opposed legs supported by said pin whereby a load is applied to said beam, a cap for said beam, opposed ears formed on said cap and having bores for said bearing pin whereby said cap is secured to said beam while adapted for some movement of adjustment relatively thereto, flanges formed on said cap adapted to overlie the opposed ends of said knife edge pivot member for limiting endwise relative sliding movement between said knife edge pivot member and beam, said knife edge pivot member and said flanges tapering relatively to one another to minimize the surface contact therebetween whereby to minimize friction inherent upon contact therebetween.

6. In a scale of the class described, a knife edge pivot member, said knife edge pivot member flaring endwardly outwardly from points inwardly of each end of its base towards its knife edge to present a peak or point surface to a limit or other surface movable relatively thereto whereby to minimize friction between said knife edge pivot member and said limit or other surface.

7. In a scale of the class described, a knife edge pivot member, a beam having a bearing surface bearing against the knife edge of said knife edge pivot member, a bearing pin traversing a bore in said beam transverse of the axis of its bearing surface and said knife edge, a load suspension link having opposed legs supported by said pin whereby a load is applied to said beam, a cap for said beam, opposed ears formed on said cap and having bores for said bearing pin whereby said cap is secured to said beam while adapted for some movement of adjustment relatively thereto, and flanges formed on said cap adapted to overlie the opposed ends of said knife edge pivot member for limiting endwise relative sliding movement between said knife edge pivot member and beam.
